UNITED STATES PATENT OFFICE

2,580,884

DRILL SHARPENING APPARATUS

Albert H. Bowman, Los Angeles, Calif.

Application May 25, 1949, Serial No. 95,210

8 Claims. (Cl. 51—219)

1

This invention relates to new and useful improvements and structural refinements in drill sharpening apparatus, and the principal object of the invention is to provide an apparatus of the character herein described which embodies in its construction a drill holder adapted for swinging or rotation on an axis guided by mechanical means so as to assure accurate formation of desired lip angle and lip clearance on the drill being sharpened.

An important feature of the invention, therefore, resides in the structural arrangement of the guiding means for the drill holder, and another feature of the invention involves the provision of means whereby the apparatus may be adjusted to form lip angles and lip clearances of different angular magnitudes, as well as to form a constant or a varying lip clearance from the periphery to the axis of the drill.

A still further feature of the invention resides in its adjustability to accommodate drills of various diameters and in its additional adjustability for the formation of different lip clearances.

An additional feature of the invention resides in the provision of gauge means for pre-setting a drill in position in the apparatus, so as to assure that the sharpening operation may be properly and correctly performed.

Some of the advantages of the invention reside in its simplicity of construction, in its adaptability for use in association with grinding wheels of different types, and in its adaptability to economical manufacture.

With the above more important objects and features in view and such other objects and features as may become apparent as this specification proceeds, the invention consists essentially in the construction and arrangement of parts as shown in the accompanying drawing in which:

Figure 1 is a top plan view of the invention showing a drill in place therein;

Figure 2 is a top plan view, similar to that shown in Figure 1, but illustrating the invention in a relatively different angular position;

Figure 3 is a side elevational view of the invention as shown in Figure 1;

Figure 4 is a perspective view of a supporting member used in the invention;

Figure 5 is a perspective view of a carrier used therein;

Figure 6 is a cross-sectional view, taken substantially in the plane of the line 6—6 in Figure 1;

Figure 7 is a cross-sectional view, taken substantially in the plane of the line 7—7 in Figure 6;

2

Figure 8 is a cross-sectional view, taken substantially in the plane of the line 8—8 in Figure 3;

Figure 9 is a cross-sectional view, taken substantially in the plane of the line 9—9 in Figure 3;

Figure 10 is a fragmentary plan view showing the gauge means used in installing the invention; and

Figure 11 is a fragmentary front elevational view of the device with the drill holder in a lowered inoperative position and with the lip-aligning gauge contacting the lip of the drill.

Like characters of reference are employed to designate like parts in the specification and throughout the several views.

Referring now to the accompanying drawings in detail, the invention consists of a drill sharpening apparatus designated generally by the reference character 20, the same including a rotatable grinding disk or wheel 22 having a flat face 24 with which the drills are engageable for grinding or sharpening purposes.

Broadly, the invention resides in the provision of means for holding a drill in a proper predetermined position relative to the face 24 of the grinding wheel so that the sharpening operation is effected while maintaining proper lip angle of the drill and controlling the lip clearance.

The means referred to in the preceding paragraph consist of a suitable stand 26 which is adapted to be secured by the bolts 28, or the like, to a supporting surface 30, such as for example, the frame of the grinder. A base member 32, preferably assuming the form of a strap, is formed with a slot 34 to receive a bolt 36 whereby

the member 32 is adjustably secured to the element 26, the base member 32 being also provided with an additional slot (not shown) to receive a further bolt 38. The bolt 38 extends through a slot 40 provided in a supporting member 42 and a suitable adjusting screw 44 extends through a screw-threaded aperture 46 into the slot 40 and is engageable with the bolt 38 for the purpose of releasably locking the latter.

The supporting member 42 is substantially horizontal and is provided with a vertical extension 48, the purpose of which will be hereinafter described. The member 42 is also formed integrally with a tubular portion 50, the bore of which provides a bearing for a pivot pin 52. The latter is formed intermediate the ends thereof with a frusto-conical shoulder 54 which engages a countersink 56 provided in the bore of the bearing 50, the shoulder 54 abutting an arm 58 to which the pin 52 is rigidly secured by means of a nut 60. Needless to say, the pin 52 is freely

rotatable in the bearing 50 and is provided with a retaining nut 62 locked by a screw and washer 64, 66, respectively (see Fig. 8) whereby the pin 52 is prevented from being withdrawn from the bearing 50.

The arm 58 is provided with a lateral extension 68 which, in turn, is formed with a horizontal bore, the axis of the latter being illustrated at 70. The bore of the extension 68 of the arm 58 accommodates a further pivot pin 72 which is similar in construction to the aforementioned pin 52 and is rigidly secured to a cam-shaped portion 74 of an L-shaped carrier 76 by means of a screw 78 extending through an aperture 80 with which the cam portion 74 is formed. A nut, washer and lock screw assembly 82 is provided on one end portion of the pivot pin 72 for the purpose of rotatably retaining the pivot pin in the extension 68, the assembly 82 being similar to the aforementioned elements 62, 64, 66.

The axis of the pivot pin 72 is also represented by the aforementioned axial line 70, and it will be noted that while the cam portion 74 of the carrier 76 is vertical, the remaining portion of the carrier is horizontal and is formed with an aperture 84 to receive a screw 86 whereby a drill holder assembly 88 is mounted on the carrier. The holder assembly 88 includes in its construction a base portion 90 which is secured to the carrier by the screw 86, while a drill cradle 92 is slideable longitudinally on the base portion 90, this being effected by providing the cradle and the base portion with coacting dovetail guides 94. Mechanical means are employed for sliding the cradle 92 on the base portion 90, these means consisting of a screw 96 rotatable in a screw-threaded lug 98 which is formed integrally with the base portion 90, the screw 96 rotatably engaging an eye 100 which is screw-threaded as at 102 into the cradle 92 and is movable in a slot 104 with which the base portion 90 is provided, as shown in Figure 7.

One side of the cradle 92 is formed with a V-shaped channel 106 to receive a drill 108, this drill being retained in the channel 106 by a laterally shiftable block 110 provided in the cradle 92. This block is actuated by means of a rotatable adjusting screw 112 and it will be observed that the block 110 is also equipped with a guiding pin 114 which slidably extends through one side portion of the cradle 92.

A stud 116 projects outwardly from one end of the cradle 92 and a clamp 118 is slidable on this stud, being adjustably secured in position thereon by a set screw 120. A shaft 122, disposed in parallelism to stud 116, is slideable through the clamp 118 and is adjustably and reversibly secured therein by an additional set screw 124. A plate or tab 126 is rigidly secured to one end of the shaft 122 and is adapted to abut the drill 108 in the manner shown, so that the position of the drill in the holder 88 may be preadjusted by setting the clamp 118, as will be clearly apparent. It is to be noted that the position of the shaft 122 in the clamp 118 may be reversed when it is not necessary to extend the shaft to accommodate extra long drills.

A drill pre-setting gauge 128 is also provided, this gauge simply assuming the form of an arm which is swingably mounted on a bolt 130, the latter extending through a screw-threaded aperture 132 formed in the aforementioned extension 48 of the supporting member 42. The arm 128 is provided at its outer end with an angulated

portion 134 which may be aligned with the lips 136 of the drill 108 when the arm 128 is swung toward the holder 88.

The aforementioned bolt 130 also carries a rotatable cam 138, a graduated indicator disk 140 and a lock nut unit 142, the latter including a nut of the "stop nut" variety, so that it does not need to be tightened against the gauge 128, but permits pivotal movement of the gauge on the bolt 130 independently of the cam 138 and disk 140. Moreover, the indicator disk 140 is convexo-concave and is formed from resilient material, so that it frictionally engages the cam 138 and discourages rotation of the latter on the bolt 130. A spacer sleeve 144 is provided between the disk 140 and the adjacent surface of the extension 48, so as to prevent the disk from collapsing and losing its resiliency.

It may be explained at this point that the aforementioned holder 88 is adjustable on the carrier 76 in the direction of the arrow 146, this being effected by simply loosening the screw 86. The relative position of the holder on the carrier is indicated by a pointer 148 formed integrally with the base portion 90 of the holder, the position of the pointer 148 being determined by means of a graduated scale 150 with which the carrier 76 is provided, as is best shown in Figure 5.

It will be also observed from the foregoing that the holder 88 together with the carrier 76 are swingable about a horizontal axis, namely, the axis 70 of the pivot pin 72, this swinging movement being indicated at 152 in Figure 3. Moreover, it is to be noted that the holder 88 and the carrier 76 are rockable together with the arm 58 on the pivot pin 52, as indicated at 154 in Figure 3, during which action the cam surface portion 74 of the carrier may engage the cam 138, as shown. However, the arm 58 together with the carrier and drill holder may be swung to a non-operative position illustrated by the phantom lines 156 in Figure 3, in which position they are supported by an arcuate stop member or strap 158 which is bolted to the arm 58 as at 160 and is provided with an angulated end portion 162 which is engageable with the under surface of the supporting member 42 when the holder is swung to the inoperative position, as shown.

It will be noted that cam 138 has an index mark or pointer 166, and the graduated disk 140 has two scales 168 and 170. The scale 168 is used when the axis 70 is set parallel with the face of the grinding wheel as shown in Fig. 1, and scale 170 has its graduations spaced further apart than those of the scale 168 to adapt it for use when the axis 70 is set at an angle to the face of the grinding wheel as shown in Fig. 2. By loosening bolt 130, the disk 140 may be turned to position the desired one of said scales at the left of bolt 130, as viewed in Fig. 3, for coaction with the index mark or pointer 166.

To aid in installing the present device upon a grinding machine, a gauge 164 is used as shown in Fig. 10. By clamping the gauge 164 in the drill holder 88, the operator may employ it to align and locate the device at a fixed distance relative to the abrasive surface 24, whereupon the bolts 36 and 38 are tightened. Fig. 10 shows the proper positions of the various elements when installing the device. In order words, cams 138 and 74 are engaged, holder 88 is horizontally disposed, and gauge 164 is secured in holder 88 and engaged with the abrasive surface 24. At this time, cam index 166 is set at zero on disk 140, and cradle 92 and base 90 are flush at their for-

ward ends, thus establishing a fixed distance from the surface 24 to the axis 70.

In use, the diameter of the drill to be sharpened is noted, and the index 166 on cam 138 is rotated relative to disk 140 to the graduation of the latter designating such diameter. The drill is now inserted in holder 88 while the latter is positioned in the dotted line position 156 of Fig. 3, thumb screw 112 is tightened to hold the drill, and shank stop 126 is adjusted to abut the drill shank. The drill is then temporarily released by loosening screw 112, whereupon the drill is rotated for alignment under gauge 128, and screw 112 is again tightened. The holder 88, carrier 76 and arm 58 are then swung upwardly about pivot pin 52 so that cam 74 is engaged with cam 138, whereupon the drill is advanced to the abrasive wheel 22 by the feed screw 96. The holder 88 is then oscillated as at 152 about pivot pin 72 while maintaining cam 74 in engagement with cam 138 so that proper lip clearance is imparted to the drill. The magnitude of this lip relief is proportional to the magnitude of its particular eccentric position and the radius of the oscillating motion imparted to the lip.

After the lip 136 of the drill 108 is sharpened in this manner, the screw 112 of the holder 88 may be loosened and the drill may be rotated so that the remaining lip or lips thereof may be sharpened in a like manner, this being repeated in instances of multi-lip drills until all the lips are sharpened to a uniform angle and clearance.

Cam 138, having a convolute form and being pre-set to a graduated scale on disk 140, acts as a regulator to equalize the radius of the oscillating motion imparted to the drill lip to conform with the variable eccentric caused by drill core thickness differences, thereby assuring an approximate sameness of lip clearance on all drills within the capacity of the device by proper setting of cam 138 to coincide with the diameter of the drill. However, the cam 138 may be set at a greater or lesser reading than the drill diameter to form a lip clearance of different predetermined magnitude without readjustment of screws or bolts.

It is to be observed that when the set-up shown in Figure 1 is used, the axis 70 is parallel to the face 24 of the wheel 22, and accordingly, a true conical grinding action is achieved, which results in the formation of a lip clearance of constant magnitude from the periphery to the center of the drill. However, if it is desired to gradually increase the lip clearance from the periphery to the center, the bolts 36, 38 may be adjusted so that the axis 70 of the pivot pin 72 is disposed, for example, at a ten degree angular deviation from the face 24 of the wheel 22, as shown in Figure 2, while the holder 88 is adjusted on the carrier 76 so that the pointer 148 is in alignment with the "49" degree mark of the scale 150. In this manner, the lip angle of the drill still remains at 59°, but the angular deviation of the axis 70 from the face 24 of the wheel 22 offsets the conical grinding action from the axis of the drill so that the lip clearance is progressively increased from the periphery to the center.

Needless to say, while in the foregoing description the lip angle of the drill was referred to as equalling 59° in accordance with conventional practice, the adjustment facilitated by the screws 36, 38, 86 may be varied so as to accommodate lip angles of other magnitude, as will be clearly apparent.

It is believed that the advantages and use of

the invention will be clearly understood from the foregoing disclosure, and accordingly, further description thereof at this point is deemed unnecessary.

Having described the invention, what is claimed as new is:

1. In a drill sharpening apparatus including a grinding wheel, the combination of a base member extending horizontally and pivotally secured to a stand, a supporting member which is substantially horizontal and is provided with a longitudinally extending slot in one end, the opposite end terminating in an integral tubular bore, a rockable arm connected to said supporting member and provided with a pivot having its axis disposed at a predetermined angle relative to the axis of said grinding wheel, a swingable carrier mounted on said pivot, a holder mounted on said carrier and adapted to support a drill with a lip of the latter in engagement with a radial face of the grinding wheel, and means comprising a cam engaging surface responsive to the swinging of said carrier for guiding the rocking movement of said arm so as to vary the position of said holder relative to said grinding wheel and thereby control the lip clearance of the drill being sharpened.

2. The device as defined in claim 1, together with means for adjusting the angle of the axis of said pivot relative to the axis of said grinding wheel, said holder being adjustable relative to the carrier and means for adjusting said holder relative to said carrier.

3. The device as defined in claim 1 wherein said means includes a cam provided on said carrier, and a rotatably adjustable cam rest on said supporting member engageable by said cam.

4. The device as defined in claim 1, wherein said means include a first cam fixed on said carrier, and a second rotatable cam adjustably mounted on said supporting member and providing a rest for the first cam, said carrier comprising an L-shaped member, and said first cam being integral therewith.

5. In a drill support for a drill sharpening machine including a grinding wheel, the combination of a base member adapted for attachment to the frame of the machine, a supporting member adjustably mounted on said base member, a rockable arm connected to said supporting member and provided with a pivot having its axis disposed at a predetermined angle relative to the axis of said grinding wheel, a swingable carrier mounted on said pivot and provided with a cam, a holder comprising a base portion adjustably mounted on said carrier, a drill cradle slidably longitudinally on said base portion, and adapted to support a drill with a lip of the latter in engagement with a radial face of the grinding wheel, means for adjusting the position of said holder on said carrier and a second rotatable cam adjustably mounted on said supporting member and adapted to be engaged by the first-mentioned cam whereby the rocking movement of said arm and the swinging movement of said carrier may be guided to vary the position of said holder relative to said wheel and to control the lip clearance of the drill being sharpened.

6. The device as defined in claim 5, wherein said holder includes a base portion adjustably attached to said carrier, a drill cradle slidably on said base portion toward and away from said wheel, and a pointer and cooperating graduated scale means for indicating the relative position of the holder on the carrier.

7. The device as defined in claim 5, together with a vertically swingable drill presetting gauge mounted on said supporting member and having a horizontal lateral arm engageable with a lip of a drill in said holder when the latter and the carrier are swung away from the grinding wheel.

8. In a drill sharpening machine, the combination with a base and integral arm means thereon, of an adjustable strap member horizontally disposed thereon and pivotally secured to said base, a supporting member pivoted to said strap member and extending horizontally, said supporting member comprising an integral tubular bore at one end for receiving a pivot pin, an arm swingably fastened by said pivot pin, said arm terminating in a second pivot pin, an L-shaped carrier pivotally secured to said arm by said second pivot pin, a drill holder mounted on said carrier, said holder having a base portion which is secured to said carrier, a drill cradle slidably secured on said base portion, a cam surface integral with said L-shaped carrier member, a second cam member secured to said supporting member and cooperating with said

first mentioned cam surface, and means comprising a graduated scale and disk for setting the second cam member relative to the first cam surface to control the lip clearance of the drill being sharpened.
